UNITED STATES PATENT OFFICE

GEORGE F. CROMPTON, OF ROCK ISLAND, ILLINOIS

VALVE-GRINDING MECHANISM

Application filed February 15, 1928. Serial No. 254,587.

My invention has reference to a valve grinding mechanism, and has for its purpose to make use of an electric drill apparatus for supplying the power for operating a valve-grinding tool. One of the objects thereof is to have the valve-grinding devices connected with the drill apparatus in a flexible manner, so that said apparatus can be held in a substantially stationary position, as by the attachment thereof to an overhead support, while the position of the valve grinding mechanism may be changed with relation thereto.

Another object thereof is to provide a variable speed gearing, by means of which the grinding mechanism can be adapted for use with electric drills of differing speeds. An attachment can thereby be made with a high speed drill motor by means of which the speed will be reduced in the grinding mechanism, so that the tool will not be operated at an excessive rate of speed, and when it is desired to use the device with a drill apparatus of lower speed, another connection can be made by means of which the speed of the tool will be made to conform with that of the drill mechanism.

Another purpose of the invention is to provide means for converting the rotary movement of an electric drill to a reciprocating movement in the valve grinding tool.

The particular construction, arrangement, and operation of the invention will be more fully understood from the following specification, taken in connection with the accompanying drawings, in which:

Fig. 1 shows an electric drill apparatus and valve grinding mechanism adapted for use therewith.

Fig. 2 is a vertical section through the casing 8, with parts therein shown in full lines.

Fig. 3 is a lower face view of the gearing for operating the valve grinding tool.

The reference number 1 indicates the casting of an electric drill apparatus, provided at one end with a handle 2 and at the other end with a shaft connection 3, on the end of the shaft of the usual electric motor contained in the casing, and not shown in the drawings. Connected with the part 3 is the

end-piece 4 of a flexible shaft 5, the other end 6 of said shaft being adapted for connection with the mechanism of the valve-grinding tool, as hereinafter set forth.

8 indicates a casing, closed by a plate 9, provided on its upper face with a pair of bearings 10 and 11, in which are rotatably held shafts 12 and 13, on which are fixed intermeshing gear-wheels 14 and 15, of varying diameters. The shaft 12 has an extension 16 for connection with the end-piece 7 of the shaft 5, said parts being fixed together by a set-screw 17 in the coupling 7, bearing against a flattened face of the shaft. Slidable on the end of the shaft 5 is a sleeve 18, attachable to the bearing 10 by set-screws 19. When thus attached an erratic action of the end of the shaft is prevented, such as might tend to disconnect such shaft from the shaft 12. At the same time the sleeve 18 serves as a handle, to assist in steadyng the tool while in operation.

The shaft 13 is also provided with an extension 20, and for carrying out the purposes of the invention the end of the shaft 5 can be connected with either the shaft 12 or shaft 13, at will. When the shaft 5 is connected with the shaft 13 the sleeve 18 is attached to the bearing 11, and to disconnect said shaft from either the shaft 12 or 13 the sleeve 18 is first loosened and raised until the screw 17 is exposed, whereupon said screw may be loosened and the parts separated.

Projected downwardly from the casing 8 is a bearing 21, in which is rotatably held a spindle 22, on the end of which is a tool 23, for engagement with the valve of an engine, as indicated in broken lines at 24. Fixed to the upper end of the spindle 22 is a crank-arm 25, connected by a pitman 26 with a relatively short crank-arm 27 on the lower end of the shaft 13. When the shaft 13 is being rotated a similar movement is given to the crank 27, which movement is imparted to the arm 25 to give a reciprocating movement thereto, and to the spindle 22.

By the adaptation of the device for connection with and operation by a commercial form of electric motor, commonly known as an "electric drill", the necessity of including

a motor as a part of the tool is eliminated, with a corresponding reduction of cost of production. The motors of the kind mentioned are commonly of two different speed facilities, one of which is much more rapid than the other, and not suited for driving a valve grinding mechanism except with a considerable reduction of the speed. The other type is fitted with a prime mover possessing a speed sufficiently slow to permit it to be applied directly to the valve grinder. For use with the more rapid type the electric motor is connected with the shaft 12, as shown in the drawings, with a reduction of speed through the gears 14 and 15, while for use with an electric drill apparatus with the slower movement a connection is made with the shaft 13, and the power is applied directly to the spindle 22. In this operation the gear-wheels and shaft 12 rotate idly. The variation of the speed of the motors mentioned is such as to call for a relative size of the gear-wheels 14 and 15 of about one diameter of the wheel 14 to three of the wheel 15. In some cases the party using the valve grinder would have access to a drill apparatus of one of the speeds referred to, and in some cases to one of the other speed, and he could conform thereto in making the connection with the valve grinding tool.

At 28 is shown a bar attached to the side of the casing 8, which may be grasped by the operator when the tool is in use. The other side of the casing may be similarly provided with a handle, if desired, for use by the other hand of the operator. In use, the drill apparatus 1 is suspended at a point above a bench or other support of the work that is being operated upon, leaving the grinding mechanism free to be moved about as desired. Changes can be made in the construction and arrangement of the invention without departing from the spirit of the invention.

What I claim, and desire to secure by Letters Patent, is:

In a valve grinding mechanism, a casing and tool spindle supported therein, a shaft rotatably mounted in said casing, and provided with means outside the casing for connection with power devices, connections between said shaft and said spindle for imparting the rotary movement of the shaft to the spindle to give a reciprocating movement thereto, an auxiliary shaft also provided with means outside the casing for connection with power devices, and gearing connecting said shafts and capable of imparting the movement of the auxiliary shaft to the first-named shaft at a reduced rate of speed.

In testimony whereof I affix my signature.
GEORGE F. CROMPTON.
